ATTACHMENT FOR PRINTING SLUG
CASTING MACHINES

Virgil A. Johnston, Fulton, Mo.

Application March 10, 1947, Serial No. 733,659

2 Claims. (Cl. 199—31)

1

This invention relates to attachments for printing slug casting machines, and more particularly to such attachments for providing full mechanical operation in both directions of the assembler block elevator.

It is a general object of the present invention to provide novel and improved attachments for printing slug casting machines whereby operation of the assembler block elevator both during lifting and lowering is effected mechanically and the cycle initiated by the operation of a simple key.

An important object of the present invention consists in the provision of attachments for application to the conventional commercial printing slug casting machine without the necessity for making any changes whatever in the structural elements thereof or of doing any cutting, drilling or other machine work on any parts of the original machine.

Another important object resides in the arrangement and construction of the several attachment parts to facilitate their incorporation with a standard printing slug casting machine with the minimum of effort and without interfering whatsoever with the normal operation of the machine or the operation with manual elevation and lowering if desired.

An important feature of the invention resides in the use of the manual lifting apparatus for the assembler block elevator for providing the attachment point for the energizing means for providing the automatic lift.

Another important feature of the invention resides in the manner of attaching, supporting and adjusting the position of the pivoted lever which lowers the elevator after the line of matrices assembled thereon are transferred to the delivery channel and the assembling elevator latch is disengaged, whereby this lever has a portion suitably extending into the path of movement of a power operated element mechanically moved at the termination of the line delivery.

A further important feature of the invention resides in the construction and assembly of the actuating key and its associated parts, including the supporting element therefor whereby it is arranged to be clamped to the keyboard frame and to provide both up and down stroke limiting adjustments for the key.

A still further important feature of the invention resides in the incorporation of the sliding latch for the assembler elevator block into a substitute slide roll bracket which also mounts the fulcrum for the latch operating lever.

Other and further features and objects of the

2

invention will be more apparent to those skilled in the art upon a consideration of the accompanying drawings and following specification, wherein is disclosed a single exemplary embodiment of the invention with the understanding that such changes and modifications may be made therein as fall within the scope of the appended claims without departing from the spirit of the invention.

10 In said drawings:

Fig. 1 is a perspective view of the keyboard, assembler block elevator and such associated portions of a conventional printing slug casting machine as are necessary for an understanding of the present invention, the attachment parts of which are shown assembled thereon;

Fig. 2 is a front elevation on an enlarged scale of a portion of the assembler block elevator, parts being broken away for clarity of illustration;

Fig. 3 is a side elevation of the elevator releasing key, key lever and key lever supporting clamp, shown attached to a portion of the machine frame;

Fig. 4 is a transverse section on line 4—4 of Fig. 3, illustrating the arrangement of the attachment of the lever supporting clamp on the frame;

Fig. 5 is a horizontal section on line 5—5 of Fig. 1, looking downwardly, showing the mounting and adjusting means for the fulcrum for the elevator return lever and its association with a portion of the frame column.

The construction and operation of the conventional printing slug casting machine is too well known to need recounting here, but it may be stated that by the operation of appropriate keys on a keyboard, resembling in some respects that of a typewriter, the operator is enabled to select a succession of matrices from which a line of type is subsequently cast. These matrices are advanced, one at a time, as their respective keys are operated, on to an assembler block. When a sufficient number of matrices to complete a line have been delivered and appropriately assembled on the block, the operator is required to actuate by hand an elevator which lifts the block to a transfer position, where an assembler latch engages and holds the elevator in this position, whereupon a line delivery carriage pawl is released and the assembled line of matrices is transferred to the left into the delivery channel from which it passes to the vise which hold the matrices while the line of type is cast therefrom. The assembling elevator

latch is released by the line delivery carriage slide so that as soon as the matrices are removed from the assembler block it may be returned manually to normal position. The operation of the hand lever for raising the elevator is extremely tiring, prevents the simultaneous use of the right hand for operating the keyboard, and may result in rapid wear in several parts of the machine, since some operators are extremely rough in their effort to hurry both the lifting and the lowering operations. By the use of this attachment the operator's hands remain in operating position at all times. Therefore, he does not have to lose time returning his hands to operating position, as in manual raising and lowering the assembler block. This permits uninterrupted fingering of the keys and greatly increases production.

In accordance with the present invention attachments are provided for incorporation with the conventional machine, to provide for automatic or semi-automatic operation of the elevator and its subsequent lowering. The elevator operation cycle is initiated by a touch on a key to the left of and in alignment with one of the rows of keys on the keyboard, which has substantially the same touch or stroke as these keys. This operation releases a latch, permitting a tension spring to lift the elevator to the transfer position where it is locked in the customary manner until the matrices have been removed. The line transfer mechanism for removing the matrices, which is mechanically operated, serves also to tension a second spring forming a part of the attachment, which on release of the elevator lowers it against the action of the lifting spring and imparts a loading to this latter spring, conditioning it for the next operation of lifting.

Referring now to the drawings, and first to Fig. 1, there is illustrated a sufficient number of parts of the conventional printing slug casting machine to illustrate the operation of the invention and to depict all of the securing points for the various attachments and the cooperating elements and parts. In Fig. 1 the keyboard is clearly illustrated at 10 and is provided with a fore-and-aft horizontal frame element 11 supporting a bearing 12 at the forward end. A corresponding frame element on the opposite side supports bearing 14 and between these is journaled a rock-shaft 15 equipped at the right side with a normally substantially horizontal handle 16 fixed thereto by a tapered pin extending vertically. To the opposite end of the rock-shaft 15 is attached the elevator operating arm 18 extending horizontally rearwardly to support pivot 20 securing the elevator link 22 to the rear end thereof. This link is pivoted at 23 to the elevator assembly 24 which supports the matrix assembler block.

In order to provide for lifting the elevator by rotation of rock-shaft 15 the conventional tapered pin which attaches handle 16 to the rock-shaft is driven out and replaced by the one illustrated at 17, whose lower end is threaded at 26 to receive the extension 28 transversely drilled at its lower end for the passage of the threaded eye rod 29 receiving the adjusting thumb screw 30. Attached to the eye at 29 is a tensioned helical spring 31 imparting the necessary rotational bias to the rock-shaft to lift the elevator to its desired position at a rapid rate of speed without bringing it too abruptly against its upper stop. The rear end of spring 31 is attached to eye 32 secured to U-clamp 33 attached to a portion 34 of the rear frame of the machine by means of a

set screw 35. The spring passes out of the way beneath the keyboard.

Referring now to Fig. 2, the elevator 24 will be seen to include the rear block 36 having spaced lower guide surfaces 37 and 38 and relieved or set back upper side surfaces 40. The guide surfaces operate between a grooved left guide 41 and a so-called slide roll bracket 42. This bracket is attached by means of dowels 44 and screws 45 to a backing element (not shown). For the purpose of the present invention the original slide roll bracket 42 is removed and a substitute of identical shape applied and accurately lined up by virtue of the dowels 44. This bracket is transversely drilled at 50 and counterbored at 51 to receive the cylindrical sliding latch 52 having the inclined nose 53 and a slightly flattened end surface 54 to engage over the shoulder at the junction of 37 and 40 on the elevator rear block. In the position shown this latch holds the elevator against rising. If the latch is withdrawn the elevator may rise under suitable energization and when it is subsequently lowered its bottom surface engages the inclined surface 53 of the latch to retract the same until its spring presses it to the position illustrated in Fig. 2 to again lock the elevator in lowered position.

In addition to the large diameter portion 52 closely fitting the bore 50, the latch has a smaller diameter extension 56 operating in the counterbore 51 and threaded on its projecting end at 57. A helical expansion spring 58 bears at its opposite ends respectively on the rear of the portion 52 of the latch and the junction of the bores 51 and 59 to urge the latch toward the left. Limited motion toward the left is achieved by threading the extension 60 on the projection 57 of the latch, which extension at the left abuts the side wall 61 of the bracket. This extension is vertically slotted as at 62 to receive the depending tongue 63 of bell crank lever 64. The slot is sufficiently long in respect to the width of the tongue so that the latch can move to the right under the action of the lowering elevator without moving the tongue. Movement of the tongue to the right, however, retracts the latch as will be apparent. The apex of the bell crank lever 64 is pivoted by a shoulder screw 65 onto the side of stud 66 threaded into the substitute bracket 42.

Lifting of the horizontal arm of bell crank lever 64 to effect latch withdrawal is under control of a key 68, which is positioned to the left of and in alignment with one of the rows of keys on the conventional keyboard 10. This key is carried at the forward end of a conventional horizontal lever 69, as more completely shown in Fig. 3 which is fulcrumed intermediate its ends on a pivot screw 70 in a bracket plate 71. The rear end of lever 69 is articulated at 72 to vertical link 73, articulated at 74, to the outer end of the horizontal arm of bell crank lever 64. Thus downward movement of the key 68 lifts arm 64 and so withdraws latch 52.

Bracket plate 71 comprises a heavy strip of metal bent to U-shape at 75 to curl around and beneath the side frame member 11 below the keyboard. Secure clamping action is effected by one or more set screws 76 opposite the short end of the U and adapted to engage the frame, as shown. In order to provide for limiting both the up and down strokes of the key lever the bracket 71 is fitted with a stamped metal attachment 78 having a flat plate portion slotted at 79 to accommo-

date screws 80 threaded in the main bar of the bracket so as to adjust the vertical position of the attachment and hence the cooperation of the lever with the laterally offset and horizontally bent upstroke limiting flange 82, which overlies the key lever 69 forward of its fulcrum 70. A parallel flange 83 positioned a substantial distance beneath the upper one receives the adjustable set screw 84 acting as a lower stop or limiting device for the lever 69.

For effecting lowering of the elevator after it has been released by the action of the key and associated parts described and lifted by the energy of spring 31, a substantially vertically disposed helical spring 85 is provided which is sufficiently stronger than 31 to serve for lowering the elevator and re-energizing spring 31 for the next lift. Such a spring is supported from eye bolt 81, which is passed through one of the several adjustment holes 82 in the horizontal arm 83 of a bracket having a vertically forked end 84 which fits beneath bolt 85 on the rear frame element 86, which bolt is normally used to hold the magazine frame to the supporting column of the original machine.

The force and motion of the lower end of spring 80 is transferred to arm 18, which is attached between the lifting link 22 and the rock shaft 15, by means of a two arm lever 87. One arm 88 of this lever extends rearwardly and is hooked to the lower end of spring 80, as shown, while the other arm 89 extends forwardly and has a horizontally right angled end 90 overlying arm 18 just forward of where it is attached at 20 to the link 22. The two parts 88 and 89 of lever 87 spring from diametrically opposite points on the periphery of a sleeve 91, where their ends are also displaced longitudinally of the sleeve, as clearly seen in Fig. 5. This sleeve is fulcrumed on a bolt 92 passing through plate 93, which is clamped between bolt head 94 and a threaded collar 95 thereon. A nut and washer 96 position the sleeve on its fulcrum bolt. The plate 93 is supported on the frame column element 100, as clearly seen in both Figs. 1 and 5. This column, for purposes of lightness, is provided with a plurality of elongated perforations 101, leaving spaced side bars 102 and 103 adjacent each perforation. Plate 93 is horizontally disposed across an aperture 101 and bears against the outer faces of these bars, and a corresponding plate 105 is arranged parallel thereto and bears on the back or inner face of the same bars. The two plates are connected together by a pair of set screws 106 and 107, spaced somewhat more closely together than the sides of perforations 101 to permit both lateral and vertical adjustment of plates 93 and 105 to fix accurately the position of the fulcrum or bearing for the lever 87.

As previously stated a source of power, usually an electric motor, drives portions of the printing slug casting machine and has adequate connections (not shown) for operating the line delivery mechanism after the assembler block and elevator have been raised to their upper position, latched there and the line delivery carriage pawl released. In order that the movement of the line delivery mechanism be as shock free as possible the operating shaft 110 therefore is adapted to be cushioned by means of air cushion cylinder 112 positioned vertically as shown in Fig. 1 to the right and rear of the assembler block and elevator and secured to a frame member (not shown). The cylinder has a closed top 113 and is fitted with a piston 114 pivoted at 115 to the

upper end of a piston rod 116 connected by pin 117 to the forked end of lever 118 integral with collar 120 non-rotatably secured to shaft 110. This lever 118 extends horizontally above and transversely to the rearwardly extending portion 88 of the elevator return lever 87, as clearly seen in both Figs. 1 and 5, and in its inoperative position holds the portion 88 depressed to cock spring 80 and free arm 18 for lifting under the action of spring 31.

In the operation of a printing slug casting machine equipped with the attachments described, the operator, in the usual manner actuates the keyboard until the desired line of matrices is arranged in the assembler block. He then touches the button 68, which withdraws latch 52 and permits the assembler elevator to be lifted through the action of tensioned spring 31 operating through levers 28 in a manner substantially identical with manual operation had pressure been applied to hand lever 16. The rotation of shaft 15 is imparted to arm 18 and a lift is given to link 22 and hence to the elevator. The elevator rises until its motion is terminated by a stop (not shown) when the assembler latch engages and holds the assembler block and elevator in raised position. This last action then effects release of the line delivery-carriage pawl and the assembled line of matrices is transferred to the left into the delivery channel by movement of the line delivery-carriage imparted to it through shaft 110 from the drive motor through any suitable mechanism (not shown). This operation lifts the lever 118 which operates the air cushion, so that it clears arm 88 of lever 87, as shown in Fig. 1. This allows spring 80 to come into play and move overhang 90 down onto arm 18, and since spring 80 readily overpowers spring 31 the elevator is lowered as soon as the assembler elevator latch (not shown) is disengaged by the line delivery carriage slide. The elevator is thus brought to its lowermost position but any tendency toward shock at the bottom is obviated by having the spring 31 now coming into full tension so as to prevent too great a final effort by spring 80 in the lowering operation. Since spring 80 has only sufficient strength to cock spring 31 it is clear that the elevator will actually lower by its own weight. The line delivery-carriage on returning preparatory to its next delivery operation lowers lever 118, which engages arm 88, cocks spring 80 and lifts overhang 90 from arm 18, preparing it for its next lifting operation of the elevator.

It will be seen that the attachments just described can all be applied to the conventional printing slug casting machine without the use of any cutting or drilling tools and that they are all properly adjustable to insure maximum efficiency of operation.

I claim:

1. A key and lever assembly for mounting on a side frame of a printing slug casting keyboard comprising in combination, a metal strip, a key secured to one end thereof, a pivot at the opposite end of said strip and a support and clamp element pivotally supporting said strip intermediate its ends and comprising a metal strap having a U-bend at its lower end to embrace said frame, a clamp screw to engage said frame to position said element thereon, a pivot for said key strip near the upper end of said strap, a stop element, means for adjusting said element vertically on said strap, said element including a laterally offset flange overhanging said strip to

limit movement of the key in one direction, a link secured to the end of said strip by said pivot and means associating said link and a locking means on said casting machine for releasing the same when the key is depressed.

2. A key and lever assembly for mounting on a side frame of a printing slug casting keyboard comprising in combination, a metal strip, a key secured to one end thereof, a pivot at the opposite end of said strip and a support and clamp element pivotally supporting said strip intermediate its ends and comprising a metal strap having a U-bend at its lower end to embrace said frame, a clamp screw to engage said frame to position said element thereon, a pivot for said key strip near the upper end of said strap, a stop element, means for adjusting said element vertically on said strap, said element including a laterally offset flange overhanging said strip to limit movement of the key in one direction, a second flange beneath the first and an adjusting screw in said

second flange adapted to limit the movement of said key in the opposite direction, a link secured to the end of said strip by said pivot and means associating said link and a locking means on said casting machine for releasing the same when the key is depressed.

VIRGIL A. JOHNSTON.
